UNITED STATES PATENT OFFICE

94,356

DESIGN FOR A COMBINED BOTTLE DISPLAY AND STAND THEREFOR

Arthur D. Oetjen, Chicago, Ill., assignor to Standard Oil Company, Chicago, Ill., a corporation of Indiana

Application October 5, 1934, Serial No. 53,496

Term of patent 3½ years

To all whom it may concern:

Be it known that I, Arthur D. Oetjen, a citizen of the United States, residing at Chicago, in the county of Cook and State of Illinois, have invented a new, original, and ornamental Design for a Combined Bottle Display and Stand Therefor, of which the following is a specification, reference being had to the accompanying drawing, forming part thereof, and in which bottle display and stand therefor, showing my new design, a portion of the pedestal being shown broken away.

I claim:

The ornamental design for a combined bottle display and stand therefor, substantially as shown and described.

In witness whereof, I have affixed my signature.

ARTHUR D. OETJEN.
